CHANGEABLE SHOW WINDOW

Charles S. Bostic, Jr., Los Angeles, Calif.

Application July 23, 1937, Serial No. 155,246

2 Claims. (Cl. 20—40.4)

This invention relates to and has for an object the provision of improved show window and display apparatus which includes a stage or display platform constructed, arranged and subject to such operation as to greatly facilitate the "dressing" and changing of displays in a show window or the like, in that, in the first place, a concealed and convenient dressing or arranging of one display on one portion of the stage may be effected while a display on another portion of the stage is presented to view, and secondly, in that the stage may be easily manipulated to quickly present different displays to view.

Another object of this invention is to provide a changeable show window construction of the character described, wherein a partitioned stage or platform is movable from a position displaying one section thereof, into a position permitting rotation of the stage to bring another section into position to be displayed upon subsequent movement of said stage back into displaying position, this arrangement not only facilitating the dressing of one section while another is displayed, but permitting the use in a comparatively small space of a large stage without objectionably obstructing the aisles, passageways and storage spaces adjacent to the stage, and also effectively screening the window space rearward and adjacent to the stage so that concealed window dressing operations may be carried on while displays are presented to view.

I have shown in the accompanying drawings a preferred form of a changeable show window embodying my invention, subject, however, to modification, within the scope of the appended claims, without departing from the spirit of my invention.

Referring to the drawings:

Fig. 1 is a horizontal sectional view of show window construction and display apparatus of this invention, showing a plurality of display platforms or stages as associated with adjacent show windows.

Fig. 2 is a sectional view taken on the plane of line 2—2 of Fig. 1.

Fig. 3 is a sectional view taken on the plane of line 3—3 of Fig. 1.

Fig. 4 is a sectional view of a variational form of the invention.

Fig. 5 is an enlarged detailed section of the track structure for the stage.

Fig. 6 is a plan view of the structure shown in Fig. 5.

Fig. 7 is a horizontal sectional view of a modi-

fied form of show window construction and display apparatus of this invention, and

Fig. 8 is a fragmentary front elevation of the apparatus shown in Fig. 1.

One embodiment of this invention as particularly shown in Fig. 1 in the accompanying drawings, comprises a show window construction consisting of show windows A and B arranged side by side and provided with the display platforms or stages C and D mounted on the floor B1 behind the glass pane B2 which latter is supported between upright columns B3. Each of the stages or platforms is provided with display sections E and F respectively, as here shown formed by a partition 9 which extends transversely across the center of the stage. At its sides the partition is provided with winglike extensions 10 and 11 projecting forwardly and rearwardly and adapted to cooperate with similar wings or extensions 12 and 13 carried by the columns B3. As here shown the stage or platform is substantially circular except for straight front and rear edges 15, but it is obvious that the stage may be of any desired shape, depending upon the construction of the show window and the space afforded therein.

In accordance with this invention, the stage or platform is mounted so that it may be moved bodily into and out of displaying position with respect to the pane B2, and when retracted from displaying position, is subject to rotation so as to present another section in a position to be displayed. Accordingly, each stage is revolvably mounted upon a carriage 16, which latter is transversely movable on tracks 17 and includes rollers 19 which ride on the tracks 17 and rollers 20 which ride upon the circular track 21 fixed to the underside of the stage. The carriage may be of any suitable construction provided it will permit of the retraction and extension of the stage relative to its display position, as well as rotation thereof to change the display, and the rollers may be provided with suitable antifriction bearings whereby the movement of the stage as aforesaid, may be easily effected by hand or otherwise, as desired. More specifically, the carriage consists of a plurality of roller mountings 22 secured together by brace rods 23. The rollers 19 are supported between depending flanges 24 upon the mountings 22, whereas the rollers 20 are supported between upstanding flanges 25 on said mountings.

Referring to Fig. 1 and particularly to window A and stage C, it is seen that the section E of the stage is in displaying position with the wings 10, 55

11, 12 and 13 substantially contacting one another, whereby to form a screen so that the space of the show window rearwardly and on each side of said section E is concealed. Where two or 5 more windows, as shown in Fig. 1, are provided with the apparatus of this invention, and the stages thereof are in the position of stage C, the entire area of the window is concealed by reason of the wings 10, 11, 12 and 13, and the rearmost 10 portions F of the stages are accessible for arranging other displays without disturbing the sections E which are in displaying position. Furthermore the stages arranged in accordance with 15 this invention and as shown in Fig. 1, afford considerable aisle space rearwardly thereof within the window, whereby the objects to be placed on display may be conveniently moved and arranged as desired, and considerable storage space will be afforded at the points G located between the 20 stages, without interfering with the operations rearwardly thereof.

It should be noted that different effects may be obtained by varying the angle of extension of 25 wings 10 and 11. As here shown, the wings 11 extend at right angles to the partition, whereas the wings 10 are otherwise angularly extended and both sets of wings will align with the angularly extended wings 12 and 13. It is obvious that the partition may be variously shaped and 30 disposed with respect to the stage and that the stage may be divided into a plurality of sections as desired, with each subject to independent use for display purposes. Assuming that the stage is retracted from display position to the dotted 35 line position shown in Fig. 1, it is then free to be rotated as shown in the right hand portion of said figure, so that the rear section F of the stage having the new display thereon, may be presented to view upon extending the stage bodily to 40 the position indicated by the full lines in the left half of Fig. 1. While this section is in display position the then rearmost section is concealed and may be utilized to arrange a new display without disturbing the display presented by the 45 other section.

It is now seen that the invention essentially comprehends the provision of a platform or stage in combination with the show window structure hereof and which is arranged to be moved first 50 bodily and transversely out of display position, then revolved to present a selected section in display position and finally moved back towards the window into cooperative relation thereto, to display the selected portion of the stage. As a result of this structure and mode of operation, a 55 comparatively large platform affording quick changes of displays, may be installed and operated in a comparatively small window space, without obstructing the floor space which is used 60 in moving objects to and from the stage or adjacent thereto in preparation for dressing the windows.

In Fig. 4 I have shown a modified form of the 65 invention wherein the stage H is circular and mounted for rotation on a fixed axis J in cooperative relation to a show window K. The stage is provided with a plurality of partitions L arranged radially thereon to define separated display sections M. The partitions are adapted to align

with wings or extensions N which extend convergently rearwardly of the window structure K, so as to act as a screen and conceal the space in the window rearwardly of and adjacent to the section M which is in displaying position. In this 5 form of the invention the platform may be intermittently or continuously rotated as desired.

In Fig. 7 I have shown another modified form of the invention wherein a plurality of show windows P are provided with substantially rectangular stages R and S arranged side by side and adapted to be angularly or diagonally retracted from display position, then rotated to dispose another section in position to be displayed and finally moved back to display position. Each 10 stage or platform is rotatably supported on a carriage T which corresponds to the carriage 16 but is movable rearwardly and angularly on diagonally extended tracks U. Each stage is provided 15 along opposite edges with upright walls V joined by a partition W, so as to define separate display sections X and Y. When one of these display sections is in display position adjacent the window, as shown in Fig. 7, the other is concealed and 20 may be utilized to arrange a new display without disturbing another section. The side walls V substantially abut the window structure so as to act as screens to conceal the window space rearwardly and adjacent to said platform. This form of 25 apparatus affords considerable working and storage space. The angular movement of the stages permits of installation of comparatively large square or otherwise shaped stages in small window spaces and permits of installation and operation of two or more stages closer together in 30 one window or in adjacent windows.

I claim:

1. A show window including a movable display platform forming a part of the floor of the window, upright partition means dividing said platform into display sections which are adapted to be selectively disposed in a predetermined display position, a carriage on which said platform is revolvable, a track on which said carriage is bodily movable into and out of said predetermined position, and stationary wings arranged to cooperate with the partition means to screen off the window space other than that occupied by the particular platform section on display.

2. A show window comprising a floor, a glass pane, a movable display platform mounted on said floor and being of less width than the floor to define an aisle rearwardly thereof, when said platform is in display position, partition means on said platform defining separated display sections which may be selectively disposed into display position, mounting means providing for bodily movement of said platform into and out of said display position and for rotation of the platform when the latter is retracted, including a carriage on which said platform is rotatable and tracks on said floor on which said platform is bodily movable into and out of display position, said tracks extending obliquely rearwardly of said pane and said carriage and platform being movable obliquely into and out of said display position.

CHARLES S. BOSTIC, JR.
